UNITED STATES PATENT OFFICE

2,460,170

PAGE END INDICATOR FOR TYPEWRITERS

John G. Furchak, Mill Valley, Calif.

Application April 8, 1946, Serial No. 660,453

4 Claims. (Cl. 197—189)

1

This invention relates to an indicator for typewriters which will indicate to the typist that the end of the paper therein has been reached.

An object of the invention is to provide a device that can be adjusted for paper of various lengths easily and quickly and when so adjusted will perform its operation efficiently.

Another object of the invention is to provide a device that is simple in construction, may be attached to typewriters of any conventional make, and will by an audible signal indicate to the typist that the end of the paper has been reached.

With the above and other objects and advantages in view the invention consists of the novel details of construction, arrangement and combination of parts more fully hereinafter described, claimed and illustrated in the accompanying drawing in which:

Figure 1 is a top plan view of an embodiment of the invention;

Figure 2 is a sectional view on the line 2—2 of Figure 1;

Figure 3 is a sectional view on the line 3—3 of Figure 2;

Figure 4 is a sectional view on the line 4—4 of Figure 3;

Figure 5 is a sectional view on the line 5—5 of Figure 3, and

Figure 6 is an elevational view of a modified form of drive.

Referring more in detail to the drawings the reference numeral 10 indicates a fragment of a conventional typewriter frame having the usual platen roller 12 mounted on the axle 14.

The embodiment of the invention comprises the housing 16 which is provided with an in-turned marginal flange 18 and the removable cover 24 which is adapted to support the housing on the typewriter frame by means of fasteners 22 which pass through the removable cover 24 of the housing to be threaded into the frame 10. The cover 24 is retained on the housing 16 by means of fasteners 20 passing through said cover to be threaded into the inturned flange 18.

As shown in Figure 3 the housing 16 has a straight wall 26 adjacent the portion of the frame to which it is attached and the body of the housing formed on the wall is semi-cylindrical in shape to accommodate the circular dial 28 provided on the complementary shaped cover 24.

The dial 28 is graduated in inches which are so designated by indicia 30 and graduations 32 properly positioned on the dial.

The cover at the center of the dial is pro-

2

vided with an aperture 34 to receive the shaft 36 on the upper end of which is secured by means of a set screw 38 a pointer 40 and the shaft is rotatably mounted in a sleeve 42 secured to the undersurface of the cover and communicating with the aperture 34.

A gear 44 is provided on the lower end of the shaft 36 and is adapted to mesh with a gear 46 secured by means of a set screw 48 to the axle 14. It will be noted that axle 14 has been provided with an extension in order that the milled hand wheel 50 may be positioned at the outside of the housing 16, the hand wheel 50 being secured to the axle by the set screw 52 and in order to properly support the extended axle 14 a bracket 54 having the aperture 56 therein for the axle has been stamped out of the bottom of the housing 16 and engages the axle as shown in Figure 2.

20 The gear 46 is provided with the same number of teeth as is the ratchet for the roller and therefore the rotation of gear 44 will be commensurable with the rotation of the gear 46. This gear 46 will rotate in unison with the roller.

25 Secured to gear 46 by a fastener 58 is a horse-shoe-shaped bell 60 which will rotate with the gear.

A clapper 62 for the bell 60 is pivotally mounted on gear 46 by means of a bolt 64 and a sleeve 66 on the bolt 64 properly positions the clapper with relation to the gear and bell as shown in Figure 5 and the clapper is tensioned by means of the spring 68 mounted on the sleeve 66 and secured at its ends to the clapper and gear as shown in Figure 5.

30 The clapper rotates with the gear and is provided with an arm 70, which will engage the striker extension 72 formed on the inner surface 40 of the housing to cause the clapper to strike the bell to indicate audibly to the typist that the end of the paper has been reached.

To insure proper engagement of the gears 44 and 46 during rotation thereof a compression 45 spring 74 mounted on the sleeve 42 engages the cover 24 and gear 44 to force the gear into engagement with gear 46, thus maintaining the gears in properly meshed relation to each other.

When it is desired to use the attachment the 50 pointer 40 is lifted against the tension of the spring 74 to disengage the gears 44 and 46 and it is set at any of the graduations desired in order that when the clapper engages the striker extension 72 the clapper will sound by means of 55 the bell an audible signal to indicate that the

predetermined setting of the dial has been reached.

In Figure 6 there is shown a modified form of drive in which the gear 46 has been replaced by a roller 74a having a friction tread 76 thereon which is adapted to frictionally drive the disc 73 which replaces the gear 44. The roller 74a is secured by means of a set screw 80 to the axle 14 of the roller 12, otherwise the structure of the remaining elements is the same as previously described.

Thus a device has been provided which can be properly set to indicate the page end and it is believed that the construction and the operation thereof will be apparent to those skilled in the art.

It is also to be understood that changes in the details of construction, arrangement and combination of parts may be resorted to provided they fall within the spirit of the invention and the scope of the appended claims.

Having thus described the invention what is claimed as new and desired to be secured by Letters Patent is:

1. A device of the character described, comprising a housing, a removable cover on said housing, a dial on said cover, a pointer on said dial coacting therewith, a vertical shaft for mounting said pointer at the upper end thereof, a gear on the lower end of said shaft, a rotatable axle below said gear, a gear on said rotatable axle coacting with the first mentioned gear to cause rotation of said pointer, an inwardly ex-

tending projection on said housing, and means on said first mentioned gear coacting with the projection on said housing to sound an audible signal when said pointer has reached a predetermined setting on said dial.

5 2. The invention as in claim 1 wherein a sleeve is provided for rotatably mounting said shaft and said sleeve at its upper end is secured to said housing and tensioning means for said first mentioned gear is mounted on said sleeve.

10 3. The invention as in claim 1 wherein the means for sounding an audible signal comprises a bell and a clapper mounted on said first mentioned gear to strike said bell when an arm formed on said clapper engages said projection on said housing.

15 4. The invention as in claim 1 wherein said means for sounding an audible signal comprises a horseshoe-shaped bell and a clapper to strike said bell to give the signal, and means is provided for tensioning said clapper.

JOHN G. FURCHAK.
